GREASE MOP FOR GRIDDLES

Don C. Steward, Phoenix, Ariz.

Application September 12, 1949, Serial No. 115,232

4 Claims. (Cl. 15—231)

1

This invention relates to a mop or squeegee for wiping excess grease from hot cooking griddles.

Briefly, the device consists in a rectangular shoe having bilateral side walls extending upwardly and inwardly. The top of the shoe carries a double row of centrally opposed hooks. A piece of absorbent material is held beneath the shoe by means of a piece of cloth wrapped around the shoe, and having its ends impaled on said hooks. A spring handle is provided with bilateral legs adapted to urge the cloth into the space between the side walls and the top of the shoe, and thus to tighten the cloth.

It has been the practice in the past for chefs or cooks in restaurants to periodically wipe excess grease and debris from the cooking griddles with an ordinary rag or towel. This practice is hazardous from the standpoint of sanitation, and because it frequently happens that the cook may burn his hand or fingers by inadvertent contact with the hot griddle. The frequent laundering of these rags or towels is also a considerable expense. By my invention I eliminate these difficulties, and provide a mop wherein the wiping element may be periodically discarded at very little expense.

It is therefore an object of the invention to provide a grease mop for cooking griddles having readily disposable and cheaply replaceable absorbent and wiping elements.

Another object of the invention is to eliminate the expense of laundering the ordinary grease rags or towels which have been used for this purpose in the past.

Still another object of the invention is to provide a grease mop with a convenient handle elevated from the hot griddle surface, so that the danger of burning the operator's hands or fingers will be eliminated.

Another object of the invention is to provide such a mop having an easily cleanable and sanitary handle, and thus to promote sanitation by eliminating the necessity for the cook to handle directly a greasy wiping rag.

Other objects will appear from the description which follows. In the drawings:

Figure 1 is a partially exploded side elevation of my device.

Figure 2 is a cross section along line 2—2 of Figure 1.

Figure 3 is a cross section similar to Figure 2, except that the elements are shown completely assembled.

Figure 4 is a plan view of the shoe hereinafter described.

2

Figure 5 is a detail side elevation showing the notches in the lower part of the handle leg.

Figure 6 is a cross section taken along line 6—6 of Figure 5.

The shoe 1 of my device consists preferably of a rectangular base plate 2, of any desired dimensions, but ordinarily considerably longer than wide, having side walls 3 extending upwardly and inwardly. These side walls extend upwardly about $\frac{1}{2}$ inch, and slope inwardly about 20 to 25 degrees from perpendicular. The upper extremities of the side walls 3 are smoothly rounded, as by turning the top edges thereof downwardly to form retaining beads, or flanges 4. Flanges 4 may extend slightly inwardly in order to increase the concavity between the inner faces of side walls 3 and the top of the base plate 2. If the beads, or flanges 4 extend sufficiently inwardly, the side walls 3 need not be turned inwardly.

The top of base plate 2 carries two longitudinal rows of centrally opposed hooks 5, designed to impale and secure fabric materials. These hooks may be formed integrally with the base plate 2 by suitably punching the plate, or they may be separately fixed to the plate.

Cooperating with shoe 1, I provide an inverted, elongated U-spring 6, centrally and bilaterally constricted to form longitudinal finger grooves 7, and handle 8. The lower legs 9 of U-spring 6 slope outwardly and terminate in inwardly turned flanges 10, forming longitudinal beads 11. When U-spring 6 is undeflected, the distance between the outer extremities of beads 11 should be at least about the width of base plate 2. Beads 11 are thus adapted to extend under retaining flanges 4, and be retained thereby, and by side walls 3, and to bear downwardly upon the outer edges of base plate 2.

The shoe 1, and the U-spring handle 6, are preferably each formed from a single piece of sheet metal of suitable thickness, strength and resilience. I have found ordinary galvanized sheet iron, about $\frac{1}{8}$ inch thick, to be suitable for the purpose.

Beads 11 are provided with transverse notches 12 cut into the lower and outer circumferences thereof. These notches are cut in such manner as to prevent longitudinal slippage of beads 11 when bearing upon a fabric material mounted on shoe 1, as hereinafter described, and to permit transverse slippage of said fabric over beads 11.

To accomplish these purposes the notches 12 may be either V-shaped in cross section as shown in Figure 5, or they may have a rectangular cross

section. The specific design of these notches, their circumferential length, their depth and spacing on beads 11 may be varied considerably depending upon the nature of the cloth they are designed to bear upon, and the tension of U-spring 6. For coarse cloth such as burlap, the notches may be sparsely spaced and shallow; for a more tightly woven and harder cloth such as canvas, more and deeper notches may be required.

The edges 13 of the notches are sharply cut, and the ends 14 thereof tapered to form an obtuse angle with the circumference of the bead 11, so that little resistance is offered by the notches to transverse slippage.

In Figure 6 it will be seen that the notch is cut primarily into the lower part of the bead circumference, and extends partially around the outer part of the circumference. The circumferential length and spacing of the notches may be varied in proportion to the degree of outward and of downward pressure with which the bead bears upon the fabric 16. The notches should be primarily distributed on the circumferential sector which bears heaviest on the cloth 16.

In use, a rectangular pad of absorbent material 15 is placed under base plate 2. This pad may consist of any coarse felt, fiber, or other cheap absorbent material.

A rectangular piece of cloth 16 is then wrapped loosely around pad 15 and shoe 1, as shown in Figure 2, and the opposite sides thereof impaled on hooks 5. This cloth consists preferably of burlap, but any cheap, strong fabric may be employed.

U-spring 6 is then manually compressed and the beads 11 allowed to expand into space 17, beneath flanges 4. In this position, as shown in Figure 3, the slack in cloth 16 is taken up by being pushed into the space 17.

When the cloth 16 becomes soiled after a day or more of use, it may be removed and discarded, and a new cloth inserted in its place.

The pad 15 will become saturated with grease, but ordinarily need not be replaced more than once or twice a month, since it does not contact the griddle. If the mop is in constant use, the pad will ordinarily not become rancid, since it is constantly being purged with fresh grease. If desired, a mineral pad may be employed, such as glass wool. The pads may be discarded after use, or, if desired, they may be solvent cleaned and re-used. Likewise, the cloth covering 16 may be cleaned and re-used, if it appears economical.

While I have described my new device in relation to its use as a grease mop or squeegee, it will be readily apparent that it is susceptible of use in any connection requiring a resilient wiping pad and holder, such for example as wiping drain-boards and windows.

Having described my invention fully in relation to a specific embodiment, I do not wish to be limited thereto, but only broadly as set forth in the following claims.

I claim:

1. A grease mop for griddles having readily disposable absorbent and wiping elements, comprising in combination a rectangular shoe having side walls extending upwardly and inwardly on each side, the upper face of said shoe carrying a double row of upwardly and centrally opposed, longitudinally disposed hooks adapted to impale and yieldably retain fabric materials against opposing bilateral tension, a layer of absorbent

material disposed under said shoe, a rectangular piece of fabric material disposed around said absorbent material and said shoe and having its two opposing edges impaled on said hooks, and an elongated U-spring handle adapted to engage, under outward tension, the inner faces of said side walls and to keep said fabric material tightened over its outer circumference, the portions of said handle contacting said fabric being transversely notched to prevent longitudinal slippage of said handle on said fabric.

2. A grease mop for griddles comprising in combination a rectangular shoe having longitudinal side walls extending upwardly and inwardly on each side, said side walls terminating in inwardly disposed anti-friction beads, the upper face of said shoe carrying longitudinally a double row of upwardly and centrally opposed, triangular hooks, a layer of absorbent material under said shoe, a rectangular piece of fabric material disposed around said absorbent material and said shoe and having its two opposing edges impaled on said hooks, and an inverted U-spring having its central portion constricted to form a handle and two outwardly extending legs, said legs terminating in transversely notched, longitudinal beads urged by said spring toward the inner faces of said side walls.

3. In a grease mop for griddles, the combination of an elongated, rectangular shoe having side walls extending upwardly and inwardly on each side thereof, the upper edges of said side walls having downwardly disposed retaining flanges, the upper face of said shoe carrying longitudinally two rows of upwardly centrally opposed hooks, and an inverted, longitudinal U-spring having its central portion constricted to form a handle and two outwardly extending legs, said legs terminating in transversely notched beads adapted to project bilaterally, under outward tension, into the spaces between the inner faces of said side walls and the upper face of said shoe.

4. A squeegee having disposable, resilient wiping elements, comprising in combination a rectangular shoe having side walls extending upwardly on each side and terminating in inwardly disposed anti-friction beads, the upper face of said shoe carrying longitudinally a double row of upwardly and centrally opposed, triangular hooks, a resilient pad beneath said shoe, a rectangular piece of cloth disposed around said pad and said shoe, and having its two opposing edges impaled on said hooks, and an elongated U-spring having its central portion constricted to form a handle and two outwardly extending legs, said legs terminating in longitudinal surfaces adapted to bear downwardly and outwardly upon said cloth beneath said beads, and notched to permit transverse slippage and restrain longitudinal slippage over said cloth.
